DESIGN FOR A MATERIALS TESTING MACHINE

Richard W. Dinzl, Narberth, Pa., assignor to
Baldwin-Southwark Corporation, a corporation
of Delaware

Application April 9, 1935, Serial No. 56,279

Term of patent 14 years

To all whom it may concern:

Be it known that I, Richard W. Dinzl, a citizen of the United States, residing at Narberth, in the county of Montgomery and State of Pennsylvania, have invented a new, original, and ornamental Design for a Materials Testing Machine, of which the following is a specification, reference being had to the accompanying drawing, forming part thereof.

Fig. 1 is a front elevation and Fig. 2 is a

perspective view of a materials testing machine showing my new design in which the dominant feature is the spectacle arrangement of the two dials disposed beside each other and positioned at the top of the machine structure.

I claim:

The ornamental design for a materials testing machine, substantially as shown and described.

RICHARD W. DINZL.
